(57) **CLAIM**

The ornamental design for a rifle receiver trigger gasket, substantially as shown and described.

DESCRIPTION

FIG. 1 is a top perspective view of a rifle receiver trigger gasket showing my new design.

FIG. 2 is a top plan view thereof.

FIG. 3 is a bottom plan view thereof.

FIG. 4 is a side elevation view thereof with the opposite side being a mirror image thereof.

FIG. 5 is a right side elevation view thereof; and,

FIG. 6 is a left side elevation view thereof.
